(57) CLAIM

The ornamental design for a vehicle floor mat, as shown and described.

DESCRIPTION

FIG. 1 is a top view a vehicle floor mat showing my new design;

FIG. 2 is a bottom view thereof;

FIG. 3 is a left-side view thereof;

FIG. 4 is a right-side view thereof;

FIG. 5 is a rear view thereof;

FIG. 6 is a front view thereof;

FIG. 7 is a perspective view thereof; and,

FIG. 8 is a perspective view thereof from another angle.

The vehicle floor mat may be used for example as a car floor mat.
